COMBINATION TOOL

Albert A. Tefft, Pawtucket, R. I.

Application October 9, 1947, Serial No. 778,950

3 Claims. (Cl. 33—93)

1

This invention relates to improvements in combination tools used by machinists.

It is greatly desirable for purposes of economy, as well as efficiency, to provide a combination tool wherein a plurality of various tools and gauges may be had by the addition or elimination of various elements to a common base.

An object of the invention is the provision for combining and attaching various elements to a common base so as to provide a large variety of tools and gauges.

Another object of the invention is the provision of a base having certain surfaces thereon which when combined with other elements will provide a square, a beveled protractor, a center head, a short square, a drill grinding gauge, a height gauge, a surface gauge, and will also provide a base and standard for supporting a dial indicator.

A more specific object of the invention is the provision of a combination tool as set forth in the above objects, which can be manufactured at a comparatively low cost of production, and which will be durable and satisfactory in use.

With these and other objects in view, the invention consists of certain novel features of construction as will be more fully described and particularly pointed out in the appended claims.

In the accompanying drawings:

Figure 1 illustrates a face view of a combination tool embodying the invention;

Figure 2 is a side elevational edge view of the tool shown in Figure 1;

Figure 3 is a similar view looking from the opposite edge of the tool;

Figure 4 is a sectional view taken longitudinally centrally through the base;

Figure 5 is a prospective view of one of the elements of the tool;

Figure 6 is a prospective view of a fragmental portion of another element forming part of the invention;

Figure 7 is a view showing the use of the tool as a short square;

Figure 8 is a view on a reduced scale illustrating the use of the tool as a drill grinding gauge;

Figure 9 is a view on a reduced scale showing the tool as being used as a surface gauge; and

Figure 10 is a view of a scratch awl.

The invention in general comprises a head or base having certain angularly related surfaces or edges, which cooperate with other straight-edged elements so as to present work engaging surfaces at certain angles to each other commonly used in the machinist's trade. Certain of the

2

elements attached to the base may be relatively moved so as to include different angles than the fixed angles above mentioned.

Referring to the drawings for a more detailed description of the invention, 16 designates generally a tool embodying one form of the invention and having a head or base 11. The base 11 is provided with a central opening 12 and four straight sides 13, 14, 15, and 16 presenting work engaging surfaces. The side 14 joins the side 13 and extends therefrom at a right angle thereto. The side 15 joins the side 14 at a forty degree angle thereto. The side 16 joins at right angles with the side 15 and includes a forty-five degree angle with the side 13. The sides 13 and 16 are joined to each other by a curved portion 17; thus there is provided a base the sides of which are angularly related to each other in angles commonly used in measuring or laying out machinists' work.

In the side 14 a recess 18 is provided in which is slidably received a straight-edged member in the form of a ruler 19. The four edge portions of this ruler may be graduated in increments of fractions of an inch in a manner which usually appears on rulers of this type. The ruler is provided with a central groove 20 extending longitudinally from end to end thereof. The ruler is adjustably secured in the recess 18 in a manner generally similar to that employed for securing the ruler in a combination square and comprises a member 21 having a projection 22 at one end thereof and a threaded portion 23 at the other end. This member is received in an opening 24 extending from the central opening 12 into the walls of the recess 18. The projection 22 engages in the groove 20 and a knurled member 26 is threadedly received by the portion 23 so as to force the ruler 19 against the bottom of the recess 18 thereby securing the ruler 19 in adjustable position to the base 11. The member 26 is recessed to receive a compression spring 25 which encircles the member 21 so as to bias the projection 22 towards the bottom of the recess 18. In the opposite side of the base there is also provided a recess 27 similar to the recess 18 and in which the ruler 19 may be received and secured in adjusted position in a manner similar to that above described, such as by employing the member 21 and its associated parts. Thus there is provided a combination square having an adjustable straight edge thereon, which is adapted for use under a greater number of particular conditions than the ordinary common combination square may be put to.

At the curved portion 17 of the base, there are provided recesses 29 and 30. These are similar to each other and extend on opposite face surfaces of the base, as best shown in Figure 3. The edge wall 31 of each recess is on a radius extending from the center of an opening 32 which extends through the walls defining the recesses. In these recesses there is mounted a short straight-edge member 33, best shown in Figure 5. The member 33 has a cored opening 34 which extends longitudinally therein from one end thereof. The opposite end is curved on a curvature similar to the curved portion 17, and this curved portion is bifurcated, providing outer arms 34. In these arms there is provided aligned openings 36.

In mounting this member 33 to the base, the arms 34 are received in the recesses 29 and 30. A threaded member 37 extends through the openings 32 and 36 and has an enlarged head 38 and a knurled nut 39 at the other end for clamping the member 33 in adjustable position to the base. There is sufficient resiliency in the arms 34 to permit their springing towards each other in clamping relation. The depth of the recesses 29 and 30 are substantially equal to the thickness of the arms 34, and the thickness of the member 33 is substantially that of the base 11, thereby providing for the face surface of the arm 33 to extend flush with the face surface of the base 11. The shank of the pin 37 is grooved as at 37' to permit the ruler 19 to extend thereby, and when the ruler is in said groove 37' the pin 37 cannot turn as the nut 39 is tightened.

The arms 34 are of a length to extend in close proximity to the edge walls 31 of the recesses 29 and 30 and is movable about the member 37 as a pivot, whereby the relation of the adjacent edge 33' of the member 33 and edge 16 may be varied. The face portion of the walls of the base adjacent to the walls 31 are graduated in degrees and a datum line 40 is provided on the arms 34 whereby the relative position of the edge 41 to the edge 16 may be determined in degrees. Thus there is additionally provided a tool which provides a beveled protractor and a drill grinding gauge as shown in Figure 8. This part 33 with the base also provides for many other uses, such for example as lengthening the base or edge 13. This may be had by swinging the member 33 to position, the edge 42 thereof in line with the edge 13 of the base. With the edge 42 of the member 33 made to extend at a right angle to the edge 13, a short square is provided for use in such condition, as shown in Figure 7, wherein a usual combination square could not be employed.

The edge portions of member 33 are also graduated in increments of inches thereby adding to the usefulness of the tool. Additional straight-edged members 43 presenting work engaging surfaces are provided whereby the member 33 may be lengthened. Each member 43 is similar and is provided at one end thereof with a tongue portion 44 which is of a size to be snugly received in the opening 34 of member 33. From the opposite end of member 43 a cored opening 45 similar in size to the opening 34 is provided whereby to receive the tongue portion 44 of an additional member 43, which may be added thereto. Member 43 may also be provided with graduation in continuation of the graduation appearing on the member 33. This latter assembly provides a height gauge, also a base and standard for a surface gauge, as shown in Figure 9. When used for a surface gauge, a clamp 46 is provided which is

slidably attached to the extended portion 48 of member 43 and carries the usual pointer 47. The pointer 47 may be substituted with a dial gauge indicator, thus the base and extended member 33 provides a proper support for the gauge.

The base is also provided with a level 49 held in position in any approved manner, such as by a set screw 50. The base also has an opening 51 extending in the side 16. The member 33 also has an opening 52 which aligns with opening 51 when the member 33 is swung to contact with the surface 16, and provides a convenient receptacle for the awl 53, shown in Figure 10. The latter mentioned position of the member 33 is shown in dot and dash lines in Figure 1.

In securing the ruler 19 in adjusted position, it frequently happens that a relative movement is had between the ruler 19 and the base 11. This necessitates the readjustment of the ruler 19. In order to maintain the proper setting prior to the tightening of nut 26, balls 54 are mounted in suitable opening 55 provided in the walls 56 and 57 of the recess 18. (See Figure 2.) Each ball is similarly mounted and urged by a spring 58 into engagement with an indentation forming the graduation on the ruler. A set screw 59 engages the spring 58 to adjust the pressure thereof to maintain sufficient friction on the ruler so as to prevent relative rotation when tightening the nut 26.

I claim:

1. A combination tool comprising a base, a recess in an edge of said base, a ruler slidably received in said recess, said ruler having graduations provided by grooves in its surface, and a spring-pressed ball located in a bore opening into said recess and urged into one of said graduation grooves to hold the ruler in adjusted position in said recess.
2. A combination tool comprising a base, a recess in an edge of said base, a ruler slidably received in said recess, said ruler having graduations provided by grooves in its opposite surfaces, and a pair of spring-pressed balls entering said recess in opposed relation to engage the opposite surfaces of said ruler, one of said balls entering a graduation groove to assist in holding the ruler in adjusted position in said recess.
3. A combination tool comprising a base having a plurality of side edges presenting work engaging surfaces, a member of substantially the thickness of said base, means at the juncture of two of said side edges including a pin with a notch extending laterally thereof and presenting an out of round cross section pivotally mounting said member on said base and comprising tongue and groove means interfitting to prevent thickening of either part of the assembly at the joint, said base having a recess in said side edges forming said juncture with the bottom of the recess at right angles to one of the edges, a ruler longer than said member presenting work engaging surfaces and slidably received in said recess against the bottom thereof and in the notch in said pin to lock the pin against rotation, said base having graduations in degrees thereon adjacent to the pivotal mounting of said member, and a datum line carried by said member whereby to determine the angular relation between said base and said member.

ALBERT A. TEFFT.
